HERSH WEISS AND ADOLF NEEDELMAN, OF PHILADELPHIA, PENNSYLVANIA; SAID
WEISS ASSIGNOR TO ROSE WEISS, OF PHILADELPHIA, PENNSYLVANIA

BATHING AND MASSAGING MITTEN

Application filed July 2, 1928. Serial No. 289,941.

Our invention relates to new and useful improvements in a bathing and massaging mitten, and has for its primary object to provide an exceedingly simple and effective device of this character which may be utilized as a washing cloth and so fitted to the hand that it will not rumple up while in use and therefore will always present an extended surface instead of a restricted one as is often the case with an ordinary wash cloth.

Another object of the invention is to provide a bathing mitten having a compartment extending over the fingers and thumb and the major portion of the palm of the hand to hold a cake of soap or other washing medium.

A further object of the invention is to provide a bathing and massaging mitten so constructed as to produce massaging elements consisting of a plurality of parallel spaced ruffled or pleated strips arranged transversely of the front portion of the mitten overlying the palm, thumb and fingers and fixed to the wall producing the pocket or soap chamber.

A still further object of our invention is to provide means for retaining the mitten on the hand against accidental displacement, said means preferably being in the form of elastic webbing located on the back portion of the wrist only.

Another object of our invention is to provide a bathing or massaging mitten of Turkish toweling or other similar cloth.

With these ends in view, this invention consists in the details of construction and combination of elements hereinafter set forth and then specifically designated by the claim.

In order that those skilled in the art to which this invention appertains may understand how to make and use the same, we will describe its construction in detail referring by numerals to the accompanying drawings forming a part of this application, in which:—

Fig. 1. is a perspective view of a bathing or massaging mitten constructed in accord-

ance with our invention and embodying one form or construction.

Fig. 2, is a section on the line 2—2 of Fig. 1 with all the parts opened or extended.

Fig. 3, is an enlarged section on the line 3—3 of Fig. 2.

Fig. 4, is a perspective view of a modified form of our bathing or massaging mitten wherein the gathered or pleated transverse strips are eliminated.

Fig. 5, is a section similar to Fig. 2 on the line 5—5 of Fig. 4.

In carrying out our invention as herein embodied, particular reference being had to Figures 1 to 3 inclusive, 6 represents the bathing and massaging mitten as a whole, comprising a back 7 and a front 8, each including a combined finger and palm section, a wrist section, and said parts are sewn together along their contiguous edges forming a seam 9 but leaving the end open at the wrist for insertion of the user's hand.

A secondary section or panel 10 comprising a combined palm and finger section 11 and a thumb section 12 and this panel overlies the front portion of the mitten and is sewn thereto preferably at the same time that the two mitten portions are sewn together and also preferably the edges of said panel are positioned to lie between the edges of the front and back portions of the mitten as plainly shown in Fig. 2.

Crosswise of the panel on the outer surface thereof are fixed a plurality of parallel gathered or pleated strips 13 which are preferably formed from the same goods as the other parts of the mitten and may be produced by taking strips of material, then doubling the two longer edges under the center of the strip, as shown in Fig. 3 and 90 stitched through the three layers of the strip and the one layer forming the panel to sew the strip in place. During the sewing operation, the strips may be gathered so as to make the strip uneven or rough for 95 massaging purposes.

As shown in Fig. 1, some of the massaging strips cross the palm of the mitten while some cross both the palm and the thumb and others only cross the finger section.

Disposed across the rear or back portion of the mitten at the wrist section is an elastic band or strip of webbing 14 having only the ends attached so as to draw the wrist portion into restricted sides while permitting it to be readily stretched and opened for the insertion of the user's hand.

The construction of the mitten described above is such that it may be used for bathing or as a wash cloth and because of the strip 13 arising from the general surface of the mitten, it may be used in exhilarating the action of the blood and therefore its utility as a massage device is highly efficacious.

In Figs. 4 and 5, we have illustrated a modification of our invention wherein two pieces of cloth are utilized to form the front portion 16 and the back portion 17 of the mitten, each of said portions comprising a combined finger and palm section, a thumb section and a wrist section, and these two portions are sewn together along their contiguous edges producing the inside seam 18.

Disposed across the front portion is a panel 19 including a combined finger and palm section 20 and a thumb section 21 with the edges thereof attached to the edges of the mitten and preferably between the edges of the two mitten portions and at the time said portions are sewn together, as plainly shown in Fig. 5.

The panel being open along its inner edge provides a mouth for the insertion of a cake of soap 22 indicated in dotted lines in Fig. 4 or other washing medium into the pocket or soap compartment formed by said panel.

Similar to the other form of our invention, an elastic band or strip of elastic webbing 23 is fastened to the wrist of the mitten in order to hold it on the user's hand and prevent accidental displacement thereof.

The cloth used for making mittens of this character is generally known as Turkish toweling but it will be obvious that other fabrics might be used with similar or approximate results or if found desirable, the mitten portion itself might be made of one material and the panel or the panel and massaging strips of another material, such as, for instance, the Turkish towel.

In actual practice a mitten is placed upon the hand of the user and the same wetted and rubbed over the body for cleansing purposes and if found desirable, soap may be rubbed on the outside thereof, or a cake of soap or other washing medium in any form may be placed in the pocket or soap compartment, so that when the mitten is rubbed over the body, a lather will be formed which will pass through the mitten material on the body being washed.

Of course we do not wish to be limited to the exact details of construction as here-

in shown, as these may be varied within the limits of the appended claim without departing from the spirit of our invention.

Having thus fully described our invention, what we claim as new and useful is:—

A bathing and massaging mitten comprising palm and back sections including thumb portions united at their marginal side and outer end edges, a panel including a thumb portion united to the palm section of the mitten forming a pocket in the region of the finger and thumb parts of said panel and rows of folded pile fabric strips secured to the panel and extending transversely thereof.

In testimony whereof, we have hereunto affixed our signatures.

HERSH WEISS.
A. NEEDELMAN.
